United States Patent [19]

Schurgin et al.

[11] Des. 261,896

[45]  Nov. 17, 1981

[54] CONTACT LENS INSERTING INSTRUMENT

[56]

References Cited

U.S. PATENT DOCUMENTS

[76] Inventors: Herbert L. Schurgin, 26 Juniper St., Wenham, Mass. 01984; Paul H. Eldridge, 14 Manning St., Ipswich, Mass. 01938

D. 236,376	8/1975	Updegraff	D16/83
D. 243,602	3/1977	Updegraff	D16/83
3,129,971	4/1964	Kobler	294/1 CA X
4,071,272	1/1978	Drdlik	294/1 CA
4,097,081	6/1978	England	294/1 CA

[] Term: 14 Years

Primary Examiner—Bernard Ansher

Attorney, Agent, or Firm—Weingarten, Schurgin & Gagnebin

[21] Appl. No.: 11,894

CLAIM

The ornamental design for a contact lens inserting instrument, as shown.

[22] Filed: Feb. 12, 1979

DESCRIPTION

[51] Int. Cl. .... D16—06

FIG. 1 is an elevation view of a contact lens inserting instrument;

[52] U.S. Cl. D16/124

FIG. 2 is a perspective view of the instrument;

[58] Field of Search .... D16/83; 294/1 CA, 64 R,

FIG. 3 is a top end view of the instrument; and

294/64 A

FIG. 4 is a bottom plan view of the instrument.

U.S. Patent

Nov. 17, 1981

Des. 261,896